UNITED STATES PATENT OFFICE

143,179

DESIGN FOR A HAND LUGGAGE CASE

George G. Barton, Racine, Wis., assignor to Hartmann Trunk Company, Racine, Wis., a corporation of Wisconsin

Application October 6, 1944, Serial No. 115,652

Term of patent 14 years

(Cl. D87—5)

To all whom it may concern:

Be it known that I, George G. Barton, a citizen of the United States, residing at Racine, in the county of Racine and State of Wisconsin, have invented a new, original, and ornamental Design for a Hand Luggage Case, of which the following is a specification, reference being had to the accompanying drawing, forming part thereof.

In the drawing:

Figure 1 is a perspective view of the top, front and end of a hand luggage case showing my new design; and

I claim:

The ornamental design for a hand luggage case, as shown.

GEORGE G. BARTON.
